UNITED STATES PATENT OFFICE.

JOHN B. MORIN, OF OAK PARK, ILLINOIS.

FUEL-CHARGED VOLATILIZER.

1,371,705.

Specification of Letters Patent. Patented Mar. 15, 1921.

Application filed December 15, 1915. Serial No. 66,919.

To all whom it may concern:

Be it known that I, JOHN B. MORIN, a citizen of the United States, residing at Oak Park, in the county of Cook and State of Illinois, have invented certain new and useful Improvements in Fuel-Charged Volatilizers, of which the following is a specification.

My invention relates to improvements in fuel-charged volatilizers, and in some features more particularly to fumigators.

Self contained fumigators are commercially known that consist, generally speaking, of a heater element and a material-receptacle, the heater element being a sheet metal shell providing a combustion chamber with side openings, having its bottom flooded with paraffin from which protrudes a central wick, and the material receptacle being

20 a sheet metal cup containing a measured charge of the fumigating material, such as paraformaldehyde, and superposed upon the heater element to close the top thereof.

A valuable feature of these commercial devices is such cheapness of construction as makes it feasible to throw away the fumigator after a single use. While features of my invention hereinafter claimed are applicable to self-heating volatilizers for other uses, I will particularly describe my invention in an embodiment appropriate for such an inexpensive fumigator.

Among the objects of my invention are to provide a fuel-charged volatilizer that 35 will extinguish itself upon the material receptacle going dry; that will burn with a delicate, uniform, well controlled flame, affording a heat of such localization and intensity as to volatilize the contents of the 40 material receptacle very rapidly with low fuel expenditure, without surface burning of the fuel, and with minimum fire risk; that is easily ignited, easy to extinguish if intentional extinguishment is desired; that 45 requires no water-bath to prevent undue transmission of heat to the floor or other support for the burner and that is improved in general and in detail in construction and mode of operation. Other objects of my invention are to make provision to minimize 50 smoke, and the soot deposit, incident to the operation of the burner; to present the paraformaldehyde in most available form for efficient volatilization and to maintain 55 throughout the mechanical structure such capacity for construction in cheap form as

will preserve the advantage of availability for purposes of single use.

In the drawing I have illustrated my invention as embodied in a fumigator of a specific form and proportions which I have commercially marketed and found to be satisfactory, and for simplicity I will confine the description of my invention to this particular utilization thereof; but it will be apparent that without change of form, (with only the omission of the paraformaldehyde), or with the material-cup and heater changed in size or design to suit special requirements, my invention may be embodied in any form 70 of self-heating volatilizer, such for instance, as an emergency, self-heating, cooking utensil for the use of travelers, campers, soldiers and others.

In the drawing—

75 Figure 1 is a vertical cross sectional view showing in full size one of the commercial sizes in which I have embodied my invention, the parts being assembled for use.

Fig. 2 is a similar view with the parts assembled for shipment.

Fig. 3 is a plan view of the burner.

Fig. 4 is an enlarged detail of burner construction.

Fig. 5 is a detail of a wick construction. 85

Referring to the drawings, 10 indicates in general the burner element, 11 the material cup, and 12 a cover-and-base member that may conveniently be marketed as part of the device.

90 I make the burner member shallow from fire sheet to fuel surface and broad at its fuel containing bottom portion, so that the fuel body 13 may be relatively thin and wide spread and may be located adequately 95 close to the plane of heat application to the fire sheet or bottom 14 of cup 11, and may be quickly influenced by the change in heat conditions due to the drying out of the material receptacle. For convenience in manufacture, and cheapness in cost, I preferably form the burner element in two pieces. The upper section 10^a of the burner I preferably make of two diameters, to provide the cup supporting ring or rim 15 and the larger 100 lower ring 16, united by the horizontal annulus or shoulder 17. The bottom member 10^b, I make with an upturned side flange 18, preferably of suitable depth to contain the fuel body, said flange being slipped into the 110 lower ring 16 of the part 10^a and stopped in its intended position by small nodes or

projections 19 (Fig. 4) struck inward in wall 16. The two parts may be soldered together or not, as preferred. Above the level of these nodes in the lower ring 15 I provide 5 orifices 20, and in the cup carrying rim 15 I likewise provide orifices 21, these orifices in both instances, preferably being regularly spaced holes, preferably of approximately the area necessary, jointly, for support of 10 normal combustion so that air supply is restricted to about the normal combustion requirements. The lower orifices 20 mainly admit air to support combustion, and the upper orifices usefully give escape to products of combustion, so that there may be a 15 tendency to local air circulation near the perimeter of the burner, in burning of the device, the air finding ingress below the shoulder 17 and exit above its level. Among 20 other advantages, this arrangement, I believe, tends to prevent wide-spread burning over the whole fuel surface, on account of the inward-draft effect adjacent to the surface of the fuel.

25 The wick structure I preferably provide in such form as to afford a long, narrow, non-central flame area, and preferably I make provision for the introduction of air within the boundaries of the flame area. In 30 the specific construction shown, the wick 22 is an annulus of material of good capillary qualities, preferably blotting paper, impregnated with solidified fuel and provided with a projecting tip 23 for easy ignition. This 35 impregnated band, is preferably confined and maintains its cylindrical form within a metal ring 25, that encompasses its lower edge portion, is preferably of large diameter to give, circularly, a long narrow flame area.

40 The wick is preferably positioned around a central boss 26 formed upwardly in the center of bottom 27 of the member 10^b, and is in effect clamped between the ring 25 and boss 26, said boss preferably having a central orifice 28 surrounded by a horizontal annular lip 29. This orifice 28 gives a desirable air ingress within the flame area that tends, I believe, to assist combustion, to facilitate flame spread along the wick when 45 the tip is ignited, and to aid in giving a desirable, lamp-like quality to the flame. To insure free passage of the air through the orifice 28, I depress small feet 30 at suitable points on the bottom of member 10^b, so that when the burner is stood on a flat 50 surface there is an air passage beneath its bottom.

The fuel may be any suitable, normally-solid hydrocarbon having a relatively low 60 flashing-point, it being my preference to use a paraffin base with which is admixed a body of wax having a lower component of carbon than the paraffin, so as to minimize smoking. I find in practice that a fuel consisting of 75 per cent. paraffin and 25 per

cent. of such a free burning wax as beeswax or ceresin, having a lower carbon content than the paraffin, gives excellent results; substantially smokeless and yet economical.

70 For performance of its primary function the cup 11 is simply a suitable container to fit closely in the top of ring 15, so as to close tightly the top of the combustion chamber. For commercial practice, however, I prefer that the cup shall be suitably constructed to receive within it the burner itself, in packaging the apparatus for shipment and shall be adapted to receive water in addition to the paraformaldehyde in use. 75 To this latter end the cup 11 consists of a closed bottom portion 11^a to interfit snugly in the top of the heater rim 14 until stopped by the shoulder 32, the lower portion of the cup containing a suitable body 33, of paraformaldehyde, to be volatilized. The cup above the fumigating body is of suitable depth and shape to receive within it, preferably in inverted position, the heater element as shown in Fig. 2. Thus the cup is 80 made deep, with a top ring 34 slightly larger than the maximum diameter of the heater, and the upper and lower zones are connected by a tapering wall 35.

85 For protection of the paraffin pending use, the material container is sealed above said paraffin. To this end I preferably employ a disk 36 of air-tight paper or card board, adapted snugly to fit in the portion 11^a and provided with a tab 37 by which 90 easy removal may be effected. The edges of this impervious paper (which is preferably paraffin impregnated) are sealed to the cup body by a ring 38 of wax, preferably soft enough not to crack or fissure easily, but offering no great resistance to the intentional removal of the paper. This form 95 of construction is valuable in that practically the entire matter foreign to the paraformaldehyde is removed when the disk 36 100 is stripped off, whereas if a mere paraffin or wax coating is flooded on the paraformaldehyde, it becomes, in the operation of the device, a needless foreign element to be 105 volatilized, tending to smoke, sputter, and otherwise detract from the perfect operation of the fumigator.

110 The cover 12 that is associated with the structure is preferably of a size and shape to telescope its side wall 39 neatly around the wall 34 of the material cup, so that, as 115 shown in Fig. 2, the device, as prepared for shipment, presents an all-metal, closed, exterior. The bottom of the cover member 120 preferably has a beading 40 around its periphery, so that, as shown in Fig. 1, when the cover is set edge downward its bottom 41 is encircled by a guarding elevation that 125 will prevent the feet 30 of the burner from readily slipping off.

In the use of the fumigator, the cover cup is preferably set edge down, as shown in Fig. 1, directly on the floor, and the burner is set thereon, and the wick lighted at the 5 projecting tip. The paraformaldehyde container has its projecting disk 36 stripped off to free the paraformaldehyde, about an ounce of water is added to the formaldehyde, to assist in producing a moist gas, and 10 the cup is pressed into place over the burner, as shown in Fig. 1. The burner operates with a very clear, delicate flame, local to the area above the wick, and in practice it is generally true that the flame appears not to 15 reach the fire plate 14 or bottom of the material cup and that very little carbon is deposited on the part 14. These effects are probably due to, or aided by, the central introduction of air, giving a very efficient 20 combustion tending to prevent the flame from concentrating into a pillar that would spread along the bottom of the material cup. Also, the air passing under the heater in reaching the central intake, tends to keep 25 the base, on which the burner is set, cool, and it does not heat up seriously in practice. Very early in the operation of the device the heat melts the fuel body, but it does not ignite over its surface, therein differing 30 from many fumigators of commercial use. The heat, properly directed and effectively distributed by the large wick, rapidly volatilizes the paraformaldehyde, and I have found the device to be very efficient in securing 35 a quick volatilization of the entire paraformaldehyde content with low fuel expenditure.

In many fumigators heretofore marketed, effort has been made to proportion the fuel 40 nicely to the paraformaldehyde body, in order that the burner might "burn out" by fuel-exhaustion just about the time that the formaldehyde was fully volatilized. The difficulty of so doing under the variant conditions to be met with in practice is obvious 45 and failure to volatilize the whole body is of frequent occurrence in practice. On the other hand, with prior devices, if the fuel content be increased, and the volatilization 50 is completed prior to fuel exhaustion, the continued fierce burning of the device is an added fire-risk and source of needless smoke and heat. With my fumigator the fuel, which is cheap, is preferably provided considerably in excess of the maximum amount 55 that might be necessary for volatilization of the paraformaldehyde, and, regardless of the presence of a relatively large amount of unconsumed fuel when the material cup 60 goes dry, the burner extinguishes itself automatically shortly after the paraformaldehyde charge is exhausted. To this end I have so constructed and proportioned the device that the increased heat within the 65 burner, due to absence of volatilizable ma-

terial in the material cup to carry off the engendered heat, results in a rapid volatilization of the pool of fuel, so charging the atmosphere within the burner with combustible vapor, that, at a critical point, 70 reached in practice a few minutes after the material cup has gone dry, the burner will be subject to a miniature gentle explosion, evidenced by a slight puffing sound and a sudden flash of flame-spread within the confines of the burner, resulting in its self extinguishment. It is to procure or facilitate this action that I maintain the bottom of the material cup relatively close to the surface of the fuel, and proportion the orifices for 75 air ingress rather closely to the needs for normal combustion, thereby securing a minimization of the time necessary to bring about the critical condition for "explosion" after the material in the cup is exhausted, 80 and minimizing the degree of suddenly-enhanced combustion that will be necessary to secure the self extinguishment.

It will be observed that in the foregoing specification I have set forth in some parts 90 matters of theory, with a view to disclosure of the best of my present understanding of the principles of construction and operation of the device, but without intent to limit my invention thereby. The facts of 95 uniform steady burning in the presence of the volatilizable material (itself volatilizing at a relatively low heat), and self extinguishment upon exhaustion of the volatilizable material have been demonstrated 100 to be as stated, and are concomitants of the construction and arrangement described.

Having described my invention, what I claim is:

1. A volatilizer comprising in combination a material container, a burner element having an open top to receive said material container, said burner element having a central bottom opening and side orifices, a wick surrounding the central opening, and a fuel body, normally solidified, embedding a portion 105 of the wick.

2. In a volatilizer the combination of a material-container and a burner element comprising a shell having an open top and a central bottom opening, a wick surrounding said bottom opening, a normally-solidified fuel body surrounding the wick, there being side openings in the shell above the fuel body level.

3. In a fumigator the combination of a burner element, a material receptacle for association with said burner element, a body of solidified paraformaldehyde in the burner element and means normally to protect said paraformaldehyde against atmospheric action comprising a removable layer of impervious material and a body of sealing material joining the edge of said impervious layer to the receptacle.

4. In a self contained volatilizer, the combination of a burner comprising a shell having suitable openings, a body of normally solidified fuel, and a wick, a material container constructed for superposition on the burner in one position and to receive the burner within it in another position, and a cover member constructed to receive the burner upon it when in one position and to 10 coat with the receptacle in another position, completely to inclose the burner between the said cover and said receptacle.

5. In a self contained, portable fumigator, constructed for single use, the combination 15 of a burner element, a material receptacle element, and a cover-and-base element, said receptacle element comprising a metal shell having a reduced bottom and a flared open top; said burner element comprising a shell

of larger lower diameter and smaller upper 20 diameter, open at its top to snugly receive the bottom of the material receptacle and containable, when reversed, within said receptacle element, and said cover member comprising a rimmed cap arranged to fit 25 over the open end of the material receptacle to inclose the burner within the latter when in packed position, and to afford a stand to receive the burner element when the fumigator is in use.

In testimony whereof I hereunto set my hand in the presence of two subscribing witnesses:

JOHN B. MORIN.
